No. 631,918.

Patented Aug. 29, 1899.

C. E. YEAGER.

LOCK.

(Application filed Apr. 19, 1899.)

(No Model.)

UNITED STATES PATENT OFFICE.

CHARLES E. YEAGER, OF PRAIRIE CREEK, INDIANA.

LOCK.

SPECIFICATION forming part of Letters Patent No. 631,918, dated August 29, 1899.

Application filed April 19, 1899. Serial No. 713,586. (No model.)

To all whom it may concern:

Be it known that I, CHARLES E. YEAGER, a citizen of the United States, residing at Prairie Creek, in the county of Vigo and State of Indiana, have invented certain new and useful Improvements in Springless Locks; and I do declare the following to be a full, clear, and exact description of the invention, such as will enable others skilled in the art to which it appertains to make and use the same.

My invention relates to improvements in side or mortise door-locks, and more particularly to that class in which the usual springs for actuating the bolt and latch mechanism are replaced by weights; and the object is to simplify and improve the construction and provide an efficient durable lock of this character.

To this end the invention consists in the construction, combination, and arrangement of the several elements of the device, as will be hereinafter more fully described, and particularly pointed out in the claim.

In the accompanying drawings the same reference characters indicate the same parts of the invention.

Figure 1 is a transverse section of a lock embodying my invention. Fig. 2 is a front elevation with the lock-plate removed. Fig. 3 is a detail perspective view of the reversible latch and its coupling-pin. Fig. 4 is a similar view of the front end of the counterbalance-weight. Fig. 5 is a perspective view of the key. Fig. 6 is a detail view, partly in section and partly in perspective, to show certain details of the bolt mechanism.

In the drawings, 1 denotes the lock-case, and 2 the lock-plate. The case is formed with the flange 3, integral guide-guard 4, and integral ward 5, and the plate 2 is similarly provided with a counterpart and aligned guide-guard 4' and a ward, the latter not being shown.

6 denotes the bolt, which has a sliding engagement with the orifice 3' in the flange and the guards 4, 4', and it is provided with a transverse shoulder 7, which limits its forward movement, and an angular shoulder 7', which abuts against the guards and limits its movement in the opposite direction. The central portion of the bolt 6 consists of an attenuated longitudinal rib 6', on the sides of which are

formed the vertical parallel dovetailed guide-grooves 6² 6² to receive the correspondingly-formed rectangular gravity-tumblers 8 8, the lower ends of which terminate in the teats 8' 8', which extend on either side of the wards 5 5', according to the position of the bolt, and lock it in either position.

9 denotes the key, the bit of which is formed with a recess 10 to clear the bolt-rib 6', and the projecting ends 11 11 of the bit come in contact with the cross-bars 8² 8² of the tumblers to raise them, so that the teats will clear the fixed wards, thus permitting the bolt to be shot or withdrawn, as desired.

12 denotes the reversible latch, which has a sliding engagement with the guide-orifice 3' in the front flange 3, and its rear end is formed with the oppositely-disposed recesses 13 13', the flanges 13² of which are each provided with an orifice 13² to receive the coupling-pin 14, according to the position of the latch. The coupling-pin 14 is formed with a longitudinal offset extension-stud 14', which engages the orifice 15² in the lip 15', formed on the counterbalance-weight 15, fulcrumed on the stud-screw 16, which secures the plate 2 to the lock-case.

The fulcrum-orifice 15² of the weight is square, as shown, to receive the correspondingly-formed socket 16', which encompasses the screw 16, and by removing this socket 16' and placing the screw in another unoccupied position in the lock the ordinary square shank and knobs (not shown) may be employed. The forward end of the weight 15 is formed with a horizontal arm 15⁴, which projects into the path of the lapping fingers 17 of the triggers 17', fulcrumed in the pistol-grip handles 18, removably secured in the escutcheon-plates 19 19, fixed on the door on opposite sides of the lock and so arranged that in grasping either handle the trigger is pressed in to raise the weight and retract the latch. The lower edge 19⁷ of the orifice 19² in the escutcheon-plate 19 is undercut, as shown, to receive the correspondingly-formed shoulder 18' of the handle, while the upper shoulder 18² is square to receive the correspondingly-formed upper edge 19² of the plate.

18³ denotes an undercut lip formed on the handle, and 19³ a similar lip formed on the inner face of the escutcheon-plate, and 20 denotes a tapering dovetailed key, which is in-

serted between the lips 18³ and 19³ to lock the parts together.

It will of course be understood that various changes in the form, proportion, and the minor details of construction may be resorted to without departing from the principle or sacrificing any of the advantages of this invention.

Having thus described the invention, what is claimed, and desired to be secured by Letters Patent, is—

In combination, the lock-case 1 provided with the bolt-orifice 3', integral guide-guard 4 and ward 5, the bolt 6 having a sliding en-

gagement with said case and formed with the attenuated rib 6' and vertical dovetailed grooves 6², and the tumblers 8 8 having a sliding engagement with said grooved bolt, and terminating at their lower ends in the teats 8', substantially as and for the purpose set forth.

In testimony whereof I have hereunto set my hand in presence of two subscribing witnesses.

CHARLES E. YEAGER.

Witnesses:

GEORGE LISTON,
OLIVER L. WILSON.
